UNITED STATES PATENT OFFICE.

SAMUEL S. SPERO, OF NEW YORK, N. Y.

BUFFING-WHEEL.

1,118,822.

Specification of Letters Patent. Patented Nov. 24, 1914.

Application filed April 28, 1914. Serial No. 335,029.

To all whom it may concern:

Be it known that I, SAMUEL S. SPERO, a citizen of the United States, residing at New York, in the county of New York and State of New York, have invented certain new and useful Improvements in Buffing-Wheels; and I do hereby declare the following to be a full, clear, and exact description of the invention, such as will enable others skilled in the art to which is appertains to make and use the same.

My invention has for its object an improvement in abrasive wheels and more particularly an improvement in buffing wheels. 15 These have hitherto been constructed of various materials, namely canvas, leather and of combinations of various materials, such as canvas or leather wheels being made by cementing a number of canvas or leather circular disks to each other and facing same with emery or other abrasive.

My invention has for its object the production of an improved buffing wheel of a new material lighter in construction and 25 more durable than those hitherto in use. For this purpose I employ ordinary scrap cork, the cork being such as is ordinarily used in the manufacture of bottle stoppers.

Referring to the drawing, Figure 1 shows a sectional view through a press which may serve in the manufacture of articles under this invention, and Fig. 2 shows a section of the product.

In the drawing 10 indicates a sub-base 25 having standards 11 secured thereto upon which a cross-beam 12 is mounted. The sub-base 10 supports a base 13 which may be of any desired shape, and this base has a cylindrical or other shaped portion terminating 40 in the shoulder 14 to form a die member 15, in which the material to be treated is placed. A head or follower 16 is slidably disposed in the die member 15, and this follower is connected as by a stem 17 to a piston 18 which actuates in a cylinder 19. Fluid is admitted into or discharged from this cylinder through piping 20.

In carrying out this invention the material being treated is heated to the desired 50 degree in the simultaneous subjection of the material to pressure. To accomplish this the follower 16 is heated as by a burner 21 which is fed from a source of supply through a piping 22, and the walls of the die member 15 are heated as by a burner 23 from the same source of supply. The pipe

22 may have a valve 24 therein to regulate the flow of gas to the burner and thereby regulate the temperature of the heating units.

The cross-beam 12 supports a hydraulic ram comprising a cylinder 25 in which is slidably mounted a piston 26, and this piston has a plunger 27 depending therefrom which passes through a stuffing box when it is desired that the piston 26 should be returned hydraulically or by other fluid pressure. The plunger 27 supports the die member 28 which conforms with the recess 15 so that when the plunger 27 is forced downwardly, the die member 28 compresses the material being treated against the follower 16 and compresses the mass to the desired degree. The die member 28 is heated by a burner 29 supplied as through a flexible 75 tube 30 which connects to the branch pipe 31 as through a valve 32.

The pipes 22 and 31 lead to any desired source of supply. The pipe 33 connects with any source of supply for a fluid pressure and the pipe 20 has connection therewith as through a valve 34. A pipe 35 connects with the supply pipe 33 as through a valve 36, and this pipe communicates with the interior of the cylinder 25 above the piston 26. When the valve 36 has been opened to admit fluid under pressure above the piston 26 it is apparent that the die member 28 is forced downwardly in the die member 15. When it is desired to raise said piston to extract the die member 28, fluid pressure is admitted through the pipe 37 and valve 38 to the under side of said piston when said piston will be raised. A waste pipe 39 is provided to enable the discharge 95 of the fluid admitted to the cylinders 19 and 25 when so desired and this pipe has connections with the pipe 20 through a valve 40 to the pipe 35 through a valve 41, and to a pipe 37 through the valve 42.

It is apparent that the drawing submitted illustrates one form of apparatus which may serve in carrying out my invention, and it is understood that I am not restricted to the identical form shown.

For the production of my improved buffing wheel, I proceed as follows:—I prepare the mold 15 of the size of the finished wheel and in this mold without the admixture of any other substances is placed a quantity of 110 granulated cork which is compressed into the sides of the mold by means of a suitable

die member 18 by hydraulic pressure. Preferably the compression takes place simultaneously with the application of heat so that the natural gum and resinous matter in 5 the cork will soften and will act as an agglutinant to bind the entire body into a uniform and coherent mass. Upon the completion of the heating and compressing, the disk so obtained is allowed to cool and requires only a surfacing with emery or other 10 abrasive to be ready for use as a buffering wheel.

I am aware that it is old in the art to use cork as an ingredient in abrasive wheels but 15 hitherto no wheel has ever been made for abrasive purposes of cork solely, homogeneous throughout and having the superior qualities of this buffering wheel.

What I claim is:—

- 20 1. As an article of manufacture, a buffering

wheel composed of granulated cork simultaneously heated and compressed.

2. As an article of manufacture, a buffering wheel composed of granulated cork heated and compressed, the particles thereof being 25 bound into a homogeneous mass by the adhesive substances naturally present in the cork.

3. A process of making buffering wheels by taking natural cork in relatively small particles and simultaneously compressing and heating the body of such cork to the shape desired. 30

In testimony whereof I affix my signature in presence of two witnesses.

SAMUEL S. SPERO.
